partnershipFiled Jan. 23, 1964, Ser. No. 339,630
24 Claims. (Cl. 114—72)

This invention relates to improvements in ship design. It relates particularly to improvements in ship design having the effect of providing a ship characterized by a high degree of structural economy. It relates more particularly to such improvements incorporated in a self-propelled ocean going marine vessel intended to carry liquid cargoes, that is, a tanker.

This application is a continuation-in-part of co-pending application Serial No. 204,314 filed in the United States Patent Office on June 22, 1962.

It is an object of this invention to provide a ship of reduced structural weight for a given cargo weight carrying capacity, or, conversely, a ship with superior cargo carrying ability per unit weight of ship constructed.

It is another object of this invention to provide a ship in which the cargo storage space within the hull has a substantially consolidated arrangement, the extent of which cargo space, as a proportion of the hull length, significantly exceeds that possible in standard hulls.

It is another object of this invention to provide a ship in which, in comparison with ships of standard design, the space for propulsion machinery within the hull is reduced to the extent of practical elimination.

It is another object of this invention to utilize parameters of hull form beyond the conventional range, doing so with significant net advantages not possible with standard hulls.

It is another object of this invention to provide a ship for liquid cargoes which is particularly advantageously arranged internally with respect to shortness of runs of in-tank cargo piping and accessibility of cargo tank valves.

It is another object of this invention to provide a ship having features which qualify it uniquely for the application of modern marine technology in the concepts of systems engineering, centralized control, and automation.

Taking as a fundamental requirement the achievement of a structurally economical design, a starting point may be that of a ship of substantially standard or conventional form having a given draft, displacement, and deadweight when floating at designed weight load condition, that is, at its designed load waterline. For purposes of clarity, draft is defined as the depth of the ship below the waterline measured to the lowest part of the hull, propellers, or other reference point, usually the lowest part of the hull, that is, the bottom line of the keel. Displacement is defined for present purposes as the full load total displacement at the summer freeboard draft, and may be said to be the sum of the light ship weight plus the full load deadweight for any given hull form and draft. Full load or total deadweight is in turn defined as the full cargo weight plus the weight of the ship's fuel, water, stores, passengers, crew, and personal effects of passengers and crew.

Within the contemplation of the present invention, a characteristic of a ship of substantially standard or conventional form is the location below the main or freeboard deck, that is, well down within the structural hull, of all of the propulsion machinery except for the propeller or propellers and, possibly, certain propulsion auxiliaries such as forced draft blowers and air heaters.

One significant measure of ship design economy of structure, at least in a cargo vessel, is the ratio of total deadweight to total displacement. This ratio, which is

always less than 1.00, tells, in effect, what weight of cargo, fuel, water, stores, etc., can be carried for a given basic or light ship weight, or, conversely, how little weight of ship is required to carry a given weight of cargo, fuel, water, stores, etc. In a cargo ship design having any commercially significant degree of structural economy, the weight of fuel, water, stores, etc., is small compared to the full load cargo weight, ordinarily not in excess of seven percent of it. Accordingly the ratio of total deadweight to total displacement is substantially a measure of the cargo carrying efficiency of a ship. The higher the ratio, that is, the closer it comes to 1.00, the greater is the economy of ship structure.

Another significant measure of ship design economy of structure in a cargo vessel is the ratio of net steel weight to weight of cargo carried or capable of being carried. This ratio is not necessarily either greater or less than unity, but as a practical matter it is always less than 1.00. The lower the ratio the greater is the economy of ship structure.

Unless otherwise defined herein, all terminology relating to ship measurements used in this specification including the claims is to be defined by the following Regulatory Body publications in current effect with the filing of the present application: (1) "Load Line Regulations," United States Coast Guard, Treasury Department, Washington, D.C., and (2) "Rules for Building & Classifying Steel Vessels," American Bureau of Shipping, New York, N.Y.

The expression "ocean-going" denotes a vessel qualifying according to the named Regulatory Bodies for foreign and coastwise service, as contrasted to shallow water, inland, or lake service.

The ship's length value used with the freeboard tables in publication (1) above is the "length between perpendiculars" (LBP). This term, used extentially in this specification, is defined in publication (1) above as the length in feet on the summer load waterline from the foreside of the stem to the aft side of the rudder post. Where there is no rudder post, the LBP is measured from the foreside of the stem to the axis of the rudder stock. For vessels with cruiser sterns, the LBP is to be taken as ninety-six (96%) percent of the total length on the designed summer load water line or as the length from the foreside of the stem to the axis of the rudder stock, if that be the greater.

As a first step according to the present invention in achieving a design which is more economical structurally than that of the presupposed ship, especially a liquid cargo ship or tanker, of conventional arrangement and form; i.e., particularly considering the ratio of length of cargo tanks to length between perpendiculars (LCT/LBP) and other parametric ratios to be noted, the length of the ship may be decreased by a relatively small but significant amount, for example, about twelve percent. In the course of this change, given service requirements are desired to remain constant as follows: hull characteristic of deadweight, and cargo characteristics of density, and, thus, specific volume. Draft is to remain substantially constant, but since the freeboard requirement is somewhat diminished by the length reduction, the depth of hull may be reduced correspondingly. Now, with the reduced length and with the constants noted, the objective becomes that of altering certain parameters, including beam and block coefficient, so as to maintain the cargo cubic to accommodate the constant cargo deadweight requirement.

To accomplish this while holding the constants noted, there must be an increase in beam and also an increase in block coefficient, the block coefficient being the ratio of the volume of the underwater body of the ship to the volume of a rectangular prism having the same length between perpendiculars and waterline breadth as the ship and a depth equal to the ship's draft.

The effect on light ship weight due to these dimensional changes involving a reduction in length-to-depth ratio and an increase in beam-to-draft ratio, overwhelmingly the effect on weight of hull structure or steel weight, will be a decrease due directly to the shortening of the ship and an increase due to the increase in the ship's block coefficient and beam. There will also be an indirect but important effect on steel weight due to the shortening of the ship. As the ship's length is decreased the bending moments in the hull structure considered as a girder will be decreased, and so longitudinal structural members of lighter cross section may be employed to satisfy a reduced section modulus requirement with a corresponding decrease in steel weight.

Since for a constant draft the section modulus requirement varies as the square of the length and approximately as the beam and block coefficient to the first power, then altogether, the effects tending to decrease the weight of hull structure due to the shortening will be greater than those tending to increase it due to the widening and making more full, with the net effect being a substantial decrease in steel weight.

The total effect of the first step geometric changes, however, and to some extent an undesirable one, is to provide a ship having not only the original or required cargo deadweight carrying ability at a reduced steel weight, but also some additional although practically unuseable ability of this kind. Furthermore, when loaded simply with the required weight of cargo, the ship will float at a reduced draft. The beam-to-draft ratio will thus be increased through both an increase in beam and a decrease in draft to a value unacceptably high according to Regulatory Body standards. How this situation comes about is explained in the following two paragraphs.

The initial shortening of the ship is effected essentially entirely in the cargo tank space because the fore and aft dimensional requirement of the below-deck machinery space is a substantially inflexible one. On the other hand, when beam is increased to restore the required cargo tank capacity this increase is effected not only in way of the ship's hull cargo tank space itself, but also in way of its propulsion machinery space. Thus with an increase in beam or breadth without a decrease in length the machinery space within the hull increases in volume. The added machinery space volume is not needed for machinery since no particular change in the ship's propulsion power requirements is contemplated. On the other hand, this added volume is not practicably useable for cargo since such use would involve the installation of rather narrow cargo tanks outboard of the propulsion machinery, an inconvenient arrangement.

The added volume of the machinery space does, however, contribute to the ship's buoyancy, and, in the present circumstance, contributes unnecessarily because the buoyancy associated with the cargo tank space has remained essentially unchanged in view of the maintenance of constant volume of this space. Accordingly when the ship is loaded with the required, predetermined deadweight of cargo it will float at a shallower draft than the original fully loaded standard ship on account of the added machinery space buoyancy which is available taken together with the reduced steel weight. The anomaly arises, therefore, of a fully loaded ship which has additional cargo weight carrying capacity, that is, a ship which can float safely and desirably at an increased draft, but the additional cargo of initially specified density to furnish this weight cannot be brought aboard.

As a second step toward improving economy of structural design according to the present invention, and as a step toward alleviating disadvantages created by the first step, the propulsion machinery is removed from inside the ship, and at least part of it is installed at the main deck level or higher while part of it is installed outside the hull below the waterline. At any rate, the

traditional propulsion machinery space within the ship's hull is left void of machinery and so becomes available to carry cargo, that is, to contribute actually to the ship's deadweight carrying ability. At this point the deadweight capacity of the vessel is higher than the original value for the standard ship which is desired to be maintained; the draft with the ship loaded to the original deadweight is less than the original full load draft of the standard ship which is desired to be held at least substantially constant, and the ratio of beam to draft remains unacceptably high. No particular change in weight of ship's structure takes place in the course of the second step.

To make full use of the former propulsion machinery space for cargo purposes without abandoning or only partially using any previously used cargo spaces, and still maintain an essentially constant original deadweight capacity, there must be a decrease in beam for effecting a reduction of total volume within the hull. This decrease, considered as a third step toward improving economy of structural design, will cause a further reduction of steel weight and so of displacement. Furthermore, the decrease in beam will cause an increase in draft of the ship floating in fully loaded condition, restoring this draft to a value at least close to that obtaining for the original fully loaded standard ship. Thus, although the decrease in beam effected in this third and last step will not offset fully the increase in beam effected as part of the first step, it will, both by itself and through its effect on draft, cause the beam-to-draft ratio of the lighter or improved ship to decrease to a value which while higher than that obtaining for the standard ship is nevertheless quite acceptable according to Regulatory Body requirements.

Block coefficient may be altered slightly in the course of the third step from its value obtaining at the ends of the first and second steps, possibly being slightly increased therefrom. If this increase should in fact take place it will have an effect of increasing steel weight and ship displacement. In total result, however, the effect tending to decrease the weight of hull structure due to the narrowing in the third step will be appreciably greater than any effect tending to increase it due to a making more full, with the net third step effect on steel weight being a decrease. Since steel weight or light ship weight is decreased as a result of the third step change in design while total deadweight carrying capacity is held constant at or restored to its original standard ship value, the ship's displacement at the fully weight loaded condition decreases further by an amount equal to the decrease in steel weight. Thus the third step change provides at least some further improvement in the deadweight-to-displacement ratio and the steel-to-cargo ratio.

The net increase in beam resulting from the three-step change in design just described will have an effect toward increasing the metacentric height of the ship. This height is a measure of transverse or anti-capsizing stability. While metacentric height must have a positive value, an indefinitely great value of this height is not desirable. This is because the greater the metacentric height the stiffer will be a given ship in rolling, that is, the shorter will be the rolling period. A ship characterized by a short rolling period or a snap roll is an uncomfortable one for personnel and one which is subjected to at least some undue stresses by high accelerations. Oil tankers in the light condition are prime examples of ships tending to have uncomfortably great metacentric heights. Since the second step of the afore-described three-step change in design calls for a substantial raising of at least a significant part of the machinery weight, however, there will be an accompanying raising of the ship's center of gravity and corresponding reduction in metacentric height to counter the increase in the height caused by the increase in beam. The characteristics of the ship in rolling will thus not be impaired.

It is to be noted from the foregoing that the characteristics of the design of this invention permit the employment of relatively large advantageous beams without the penalties such a procedure would inflict upon standard hulls. As has been shown; even larger beams (first step) would be required for a conventional hull. This plus the propulsion machinery weight all at the traditional lower location would preclude attaining acceptable metacentric heights. Thus, the basic design employs a parameter beyond the normal boundary and does so without penalty, but indeed with cumulative advantages.

Along with the raising of at least some of the propulsion machinery, it is also within the contemplation of the present invention that certain tanks normally located below a ship's main deck will be raised to the main deck level or higher. These tanks include those for fuel oil and fresh water, and when filled with the liquids which they are intended to contain represent a considerable weight. This weight carried topside will, like that of the propulsion machinery, tend to reduce the metacentric height and so keep the ship from being unduly stiff in rolling.

Raising of at least part of the propulsion machinery and the accommodations for some liquids to the main

ployed in the ship of this invention and still maintain satisfactory flow of water to the propellers, a difficult accomplishment for the standard hull with large beam and block (Note: Page 902 of Reference B following).

5 The overwhelming number of cargo ships built according to traditional design, whether they be dry cargo ships of all kinds on the one hand or liquid cargo ships of all kinds on the other hand, have deadweight-to-displacement ratios of less than 0.80:1. As an example in the 10 case of liquid cargo ships, that is, tankers, reference may be had to the article (Reference A) "Some Aspects of Large Tanker Design" by W. O. Nichols, M. L. Rubin, and R. V. Danielson. This article was presented as a paper at the Annual Meeting of the Society of Naval Architects and Marine Engineers held on November 15 17-18, 1960, at New York, N. Y., and occupies pages 743-835 of volume 68 of the Transactions of the Society of Naval Architects and Marine Engineers (1960). On pages 804-806 this article presents as an appendix the 20 essential characteristics of a group of nine modern tankers in commercial service ranging from 25,400 to 106,600 total deadweight tons at design summer free board draft, and certain data either taken directly or calculated from this appendix are given in the following Table I:

Table I

Ship-----	A	B	C	D	E	F	G	H	J
Dwt. (tons)-----	25,400	27,000	28,250	29,350	33,150	46,100	67,450	71,300	106,600
Δ (tons)-----	32,740	35,100	36,450	37,850	43,010	59,160	86,730	91,910	137,200
$Dwt./\Delta$ -----	0.775	0.769	0.775	0.776	0.771	0.779	0.778	0.779	0.777
LBP/D -----	13.0	13.1	13.5	14.0	13.9	14.1	13.7	13.7	13.3
B/H -----	2.33	2.52	2.54	2.55	2.64	2.70	2.38	2.61	2.69
C_b -----	0.758	0.758	0.765	0.772	0.772	0.756	0.799	0.757	0.794
LCT/LBP -----	0.609	0.609	0.622	0.634	0.619	0.624	0.672	0.659	0.654

deck level or higher affords to this part of this machinery and these liquids or their accommodations a fair degree of freedom of fore and aft location. By shifting this machinery and these liquids either forward or aft, the longitudinal location of the center of gravity of the ship may be shifted also in the corresponding direction. For a stable ship to be in equilibrium when floating in still water, its center of buoyancy must be on a vertical line with its center of gravity. Location of the center of buoyancy is dependent upon the shape of the ship's underwater body which is in turn controlled to at least some extent by the shape of the ship's waterplane area, that is, the shape of the area through the ship at the waterline. Shape or configuration of the waterplane area affects the characteristics of the ship in longitudinal stability or pitching. These characteristics are also designated generally as sea kindliness. Certain waterplane shapes are more conducive to sea kindliness than others. With a considerable amount of topside machinery and liquid weight shiftable longitudinally in a ship constructed according to the present invention to keep the centers of gravity and buoyancy properly aligned, the waterplane area and underwater body of the ship may be shaped to at least some extent for the purpose of achieving a high degree of sea kindliness, and hull efficiency in respect of resistance characteristics and powering requirements.

In the design, construction, and operation of oil tankers it has traditionally been a problem to dispose the center of buoyancy sufficiently far forward to avoid excessive trim by the head. This is because of the very full stern which must be provided on a tanker having its propulsion machinery in the customary aft location. In a ship constructed according to the present invention it is possible to provide a somewhat less full stern, despite the increase in beam and block coefficient, and so let the center of buoyancy have a desirable shift forward with the center of gravity being movable with it through the movement of topside machinery and liquids. Furthermore, these parameters of large beam and block coefficient may be em-

ployed in the ship of this invention and still maintain satisfactory flow of water to the propellers, a difficult accomplishment for the standard hull with large beam and block (Note: Page 902 of Reference B following).

40 In the foregoing tabulation, Dwt. designates total deadweight in tons; Δ designates total displacement in tons; LBP designates length between perpendiculars; D designates molded depth from the upper or freeboard deck to the keel; B designates molded breadth or beam; H designates molded draft from the waterline corresponding to summer freeboard to the keel; C_b designates block coefficient, and LCT designates the overall length of cargo 45 tanks. All length values are, of course, employed with consistent units for ratio purposes as are all weight values.

Table I extends over a wide range of deadweight values, and it is to be observed particularly that no one of the 50 nine ships making up the tabulated group has a ratio of total deadweight to total displacement ($Dwt./\Delta$) greater than 0.779. The smallest value of length-to-depth ratio (LBP/D) is 13.0; the largest value of beam-to-draft ratio (B/H) is 2.70; the largest value of block coefficient (C_b) is 0.799, and the largest value of the ratio of the length of 55 the cargo tanks to the length between perpendiculars (LCT/LBP) is 0.672.

The overwhelming number of cargo ships built according to traditional designs, whether they be dry cargo ships of all kinds on the one hand or liquid cargo ships of 60 all kinds on the other hand have ratios of net steel weight to design cargo weight of greater than 0.200:1. As an example in the case of liquid cargo ships, that is, tankers, reference may be had to the article (Reference B) "Modern High Speed Tankers" by L. C. Long, J. L. Stevens, Jr., and J. T. Tompkins, Jr. This article was presented as a paper at the April, 1960, meeting of the Hampton Roads Section of the Society of Naval Architects and Marine Engineers, and occupies pages 887-958 of volume 68 of the Transactions of the Society of Naval Architects and 65 Marine Engineers (1960). On pages 888 and 889 this article presents in tabular form the essential characteristics of a group of six modern tankers in commercial service (none the same as those previously noted from the Nichols article) ranging from 19,183 to 66,532 total deadweight tons at design summer freeboard draft, and cer-

tain data either taken directly or calculated from this tabulation are given in the following Table II:

Table II

Ship	A	B	C	D	E	F
Dwt. (tons)	19,183	38,911	37,689	41,173	60,615	66,532
A (tons)	25,510	49,660	50,176	52,302	77,029	82,678
Net Steel Weight (tons)	4,486	8,379	9,374	8,759	13,241	12,896
Cargo Oil Weight (tons)	18,098	37,896	36,634	38,769	56,257	62,174
Net Steel/Cargo	0.248	0.221	0.256	0.226	0.235	0.207
LCT/LBP	0.565	0.635	0.584	0.631	0.639	0.638

Although not as wide as that of Table I, the range of deadweight values over which Table II extends is still a fairly wide one, and one which falls almost entirely within the range of Table I. Hence the tankers represented in and by the two tables are in large measure comparable from table to table. It is to be observed particularly that no one of the six ships making up the tabulated group of Table II has a ratio of net steel weight to cargo weight less than 0.207 or a ratio of length of cargo tanks to length between perpendiculars greater than 0.639.

The ship of this invention is characterized by a ratio of total deadweight to total displacement not less than 0.80:1, especially such a ratio in the range from 0.81:1 to 0.86:1, which represents a high range of this ratio never before attained in self-propelled cargo-carrying vessels for ocean service. It is also characterized by a ratio of net steel weight to cargo weight not in excess of 0.190:1, especially such a ratio in the range from 0.140:1 to 0.180:1. The combination of ship design features which permits reduced light ship weight, increased cargo storage capacity, efficient cargo and ship handling, safety, and stability in the ship of this invention may be described generally as follows: a ratio of length between perpendiculars to molded depth (LBP/D) not greater than 13.30:1, a ratio of molded beam to molded draft at summer freeboard (B/H) not less than 2.80, a block coefficient (C_b) calculated using length between perpendiculars as the length value not less than 0.80, and a ratio of length of below-deck cargo space, especially cargo tank space, to length between perpendiculars (LCT/LBP) not less than 0.70:1.

The preferred embodiment of this invention is a ship characterized by the numerical parameters just given and comprising a hull having a main or freeboard deck, a prime mover positioned above the freeboard deck, and at least one propulsion unit situated below the water line at the stern of the ship secured to the exterior surface of the hull. Internally there are a pair of fairly closely spaced longitudinal bulkheads running substantially the full length and depth of the vessel, and defining between them a centerline cofferdam or chamber which may be used to accommodate cargo tank valves in the case of a tank ship and some auxiliary machinery.

The hull should have a hydrodynamically efficient stern, such as a scow stern or a destroyer stern. The prime mover, located or on above the freeboard deck, possesses means for providing a source of power to propel the ship. The propulsion unit comprises, generally, a propulsion motor adapted to be energized by the power providing means of the prime mover unit and means actuated by the propulsion motor for propelling the ship. These propelling means are preferably, although not necessarily, coaxially mounted, co-rotating or contra-rotating propellers oriented to provide conventionally directed thrust (forwardly along the longitudinal axis of the hull) to drive the ship.

Standard shipbuilding materials are contemplated to be employed throughout in constructing the ship of the present invention. Specifically, it is not contemplated that any improvement will be effected in deadweight-to-displacement ratio and/or steel-to-cargo ratio simply by

switching from conventional materials such as mild steel to highly alloyed and high strength steels and using reduced scantlings for this reason only, or switching to non-ferrous materials such as structural aluminum. While such switches or substitutions might be possible in some cases, the resulting overall construction costs would exceed those for standard procedure, and a great deal of the economy achievable by the present invention would be lost.

10 The nature and substance of this invention as well as its objects and advantages will be more clearly perceived and fully understood by referring to the following description and claims taken in connection with the accompanying drawings in which:

15 FIG. 1 represents an outboard profile view of a tanker embodying the design features of the present invention, some external structure being broken away for purposes of showing internal machinery arrangements, and certain internal deck and bulkhead structure being shown in dashed outline;

20 FIG. 2 represents a sectional plan view of the tanker of FIG. 1 just below the freeboard deck taken along line 2-2 in FIG. 1 looking in the direction of the arrows;

25 FIG. 3 represents a transverse sectional elevation view of the tanker of FIG. 1 at the midship section taken along line 3-3 of FIG. 1 looking in the direction of the arrows;

30 FIG. 4 represents an outboard profile view of a portion of the superstructure of a tanker constituting another embodiment of this invention in which fuel oil tanks are carried on a tank space deck above the freeboard deck;

35 FIG. 5 represents a plan view of the tank space deck of the tanker of FIG. 4 taken along line 5-5 in FIG. 4 looking in the direction of the arrows, and

40 FIG. 6 represents an outboard profile view of the stern portion of the tanker of FIG. 4 in which fresh water tanks are located in the stern superstructure.

45 Referring now to the drawings in detail, especially FIGS. 1, 2 and 3 thereof, a tanker 10 embodying the design features of this invention includes a hull 11 having a bow portion 11a and a stern portion 11b. The freeboard deck 12 of the tanker is represented by a dashed line in FIG. 1, and certain upper and lower longitudinal interior passageway decks or platforms shown in dashed line are designated 13a and 13b. These decks or platforms are of only very narrow width between longitudinal bulkheads as may be seen most clearly in FIG. 3.

50 A prime mover unit or machinery section 14 is disposed on or above the freeboard deck, preferably at or near the stern portion 11b of the vessel. Machinery section 14 serves as the power source for two propulsion units or "pods" 15a and 15b located equally port and starboard well below the water line 16 at the stern portion 11b of the hull 11. Each propulsion unit is secured to the exterior surface of the hull and, taking unit 15b as an example, comprises a pair of coaxially-mounted, contra-rotating or co-rotating propellers 17 and 18 driven by a motor device 19. The power to drive motor device 19 itself is brought to propulsion unit 15b by appropriate power transmission means 20. Similar means, of course, 55 extend to unit 15a. Motor device 19 in propulsion unit 15b may be one that is energized by steam, compressed gas, or hydraulic fluid, as well as by electricity.

60 The stern portion 11b of the hull is designed with a flat bottom 21 extending upwardly from the keel 22 of the ship 10, such design usually being designated as a "scow type" stern. Propulsion units 15a and 15b are preferably secured to hull 11 on the flat bottom portion of the stern and oriented to provide thrust along the fore-and-aft or longitudinal axis of the ship. Hull 11 65 may also be provided with a bow nodule or bow thruster 23a to improve maneuverability of the vessel, and also a stern thruster in each of the propulsion pods, thruster 23b in pod 15b being shown.

70 Tanker 10 includes a superstructure section 24, that is, a section at and above the level of the main or freeboard

deck 12, which comprises various bridges and boat decks. Additionally, and in particular, it comprises structural tank spaces 25 for carrying fresh water. The whole section 24 may be located more or less amidships or as desired to suit design conditions. The forward perpendicular (F.P.) and the aft perpendicular (A.P.) are indicated in FIG. 1 at locations consistent with Regulatory Body determinations given earlier in this specification. The distance between these perpendicularly is the vessel's length between perpendicularly (LBP).

Tanker 10 is also provided with a very important internal design feature most clearly apparent in FIGS. 2 and 3. This is the provision of longitudinal bulkheads 26 and 27 extending all the way from the forward peak bulkhead 28 to the stern of the ship. The two longitudinal bulkheads are essentially equally offset port and starboard from the longitudinal centerline of the ship, and extend the full depth of the ship from the main strength deck 12 to the keel 22. Their lateral or transverse spacing is not more than about ten percent of the beam of tanker 10 at its midship section. Otherwise the tanker is of typical longitudinally framed construction employing heavy transverse webs such as 29a with large open regions as shown in FIG. 3, although not in FIG. 2, between transverse bulkheads 29b of which at least every other one is liquid tight.

In a ship having the prime mover unit above the freeboard deck and separated from the propulsion units 15a and 15b located at stern 11b, the double bulkhead construction provides a space 39 for the routing of feeder cables 20 or other power transmission means down from machinery section 14, as well as space for cargo handling machinery, not shown. Specifically in the case of a liquid cargo ship such as tanker 10, the space between bulkheads 26 and 27 can serve as a cargo pump room. Throughout the ship, therefore, substantially all auxiliary machinery, power cables, cargo valves, cargo piping and the like can be concentrated in the space or longitudinal cofferdam 30 between bulkheads 26 and 27, thereby removing these items from regions otherwise used for cargo storage, and in particular making valves more accessible and piping runs shorter than in the conventional tanker design. With increased concentration of auxiliary equipment, the amenability of this equipment to reliable and economical centralized control and/or automation is enhanced. Likewise there will be great convenience in having the upper and lower internal longitudinal platforms 13a and 13b. Continuous internal access through the vessel may be provided by liquid-tight doors in the transverse bulkheads at the platform levels.

The location of machinery section 14 and structural fresh water tanks 25 at and above the freeboard deck and propulsion units 15a and 15b outside of the hull frees the interior of the hull of the cubic requirements of this equipment and structure. Tank sections 31a through 31h (port) and tank sections 32a through 32h (starboard) which provide the cargo and, if necessary, some ballast carrying capability of ship 10 extend throughout the very substantially greater part of the length of the hull 11. By use of non-tight transverse bulkheads, combinations for filling and discharge purposes may be made of tank spaces 31a and 31b, 31c and 31d, 31e and 31f, 31g and 31h, 32a and 32b, 32c and 32d, 32e and 32f, and 32g and 32h. The total length of the below-deck tank space, that is, the tank space length extending from the forward bulkhead of space 31a (or 32a) to the aft bulkhead of space 31h (or 32h), is designated LCT in FIG. 2.

Directly aft of the cargo spaces within the hull are fuel oil tanks 33 and 34 and salt water ballast tanks 35 and 36, and still farther aft are ballast tanks 37 and 38. Located between these ballast tanks on the outside and longitudinal bulkheads 26 and 27 on the inside are washdown tanks 39 and 40. These tanks may be adapted to contain washing materials, fresh water and detergent-water mixture, for example, for cleaning the cargo tanks. Aft of the

washdown tanks but still between ballast tanks 37 and 38 is steering engine space 41.

At the forward bulkhead of the steering engine space the longitudinal bulkheads 26 and 27 go out of contact with the underside of freeboard deck 12, and decrease in height from their normal upper edges by an amount equal to the height of the steering engine space. Below this space these bulkheads continue all the way to the stern of the ship, and the rotating rudder stock passes down between them. The deck of steering engine space 41 is at the same level as upper platform 13a between the longitudinal bulkheads. Directly forward of the cargo tank spaces are forward salt water ballast tank 42 and chain lockers 43 and 44.

15 The hull 11 of the tanker 10 shown in the drawings possesses several features, briefly noted above, which, together with reduced structural weight and, conversely, increased dead-weight for a given displacement, provide a vessel with exceptional stability and efficiency. The hull itself is of relatively reduced length and relatively increased beam compared with the hulls of cargo ships of conventional design. Generally, it may be stated that the hull of a ship having the design features of the present invention has a ratio of length between perpendicularly to molded depth (LBP/D) not greater than 13.30:1, especially such a ratio in the range from 11.50:1 to 13.00:1; a ratio of molded beam to molded draft at summer freeboard (B/H) not less than 2.80:1, especially such a ratio in the range from 2.90:1 to 3.10:1; a block coefficient (C_b) calculated using length between perpendicularly as the length value not less than 0.80, especially such a coefficient in the range from 0.81 to 0.85, and, particularly in the case of a tank ship, a ratio of length of below-deck cargo space to length between perpendicularly (LCT/LBP) not less than 0.70:1, especially such a ratio in the range from 0.70:1 to 0.82:1. This design will reduce the frictional resistance as the vessel moves through the water on account of reduced wetted hull surface area, and will increase the transverse stability of the ship to 40 render safely practicable the above-deck location of at least part of the propulsion machinery and some substantial liquid weights.

A flat horizontal bottom representing a lateral extension of keel 22 obtains over the greater part of the length 45 of the hull 11. At the location 45 (an imaginary line athwartships), the flat horizontal bottom surface slopes upwardly and rearwardly in a continuous flat although not horizontal surface characteristic of a scow-type stern. The upward slope continues to a position above a rudder 46 where a transom 47 constitutes the extreme stern surface of the vessel 10. Forward of position 45 and aft of position 48 the sides 49 and 50 are substantially flat and parallel and are disposed approximately vertically. Aft of position 45 the sides 49 and 50 converge as shown 55 in FIG. 2. Such convergence minimizes inward induction of the water flow toward the stern and therefore also minimizes cavitation, since inwardly flowing water under these conditions entrains great quantities of air. The location of propulsion units 15a and 15b under the flat, upwardly sloping surface 21 of stern portion 11b is optimal since the region in which the co-axial propellers of each propulsion unit are to operate according to this design is one in which the water is substantially free of entrained air.

60 Beyond improving the efficiency of the propulsion system, the scow-type construction offers the additional advantage of making a greater portion of cubic within the hull available to cargo. Thus, the substantially rectangular cross section of the hull is maintained throughout its length, and only aft of position 45 is the depth of the hull varied. Furthermore, with the scow-type construction, the sloping bottom 21 of the stern provides a plane surface under which the propulsion units can be conveniently mounted. The angle of the sloping bottom 21 75 with respect to the horizontal keel or bottom 22 can be

maintained substantially constant regardless of the type of cargo the ship is conditioned to carry, thereby permitting the propulsion units 15a and 15b to be conveniently fabricated in a "pod" form and yet fit a variety of hulls which are adapted for different cargoes.

The machinery section 14 may be situated nearer the amidships location of the vessel, or it may also be located adjacent or within the superstructure 24. In some designs, it may be desirable to position the superstructure 24 appreciably toward the bow with the machinery section 14 located amidships. In any event, as a result of the unit construction of the machinery section 14 and the superstructure 24, the designer is free to position these assemblies along the longitudinal axis of the hull in order to position the longitudinal center of gravity at the optimum position for a given hull construction and its attendant longitudinal center of buoyancy location. Thus, the hull can be designed to provide the optimum requirements for resistance to sea motion and for stability; and then, subsequently, the package or unit of the machinery section 14 and superstructure 24 can be positioned along the hull in order to obtain a compatible location of the longitudinal center of gravity thereby providing the proper trim. Proper positioning of the machinery section 14 and superstructure 24 (with its living quarters, operational stations, etc.) also allows for posturing the load on the ship in order to obtain the optimum bending moment, and thereby effecting the least stress and strain on the ship considered as a girder.

In constructing a new ship or in modifying an existing one, the structures including the prime mover unit or machinery section 14, and the "pod" propulsion units 15a and 15b, can be fabricated separately from the hull of the ship. Similarly the superstructure 24 can be constructed with the prime mover unit independently of the hull. Regardless of whether the hull is to be adapted for the carrying of containers, vehicles, bulk dry cargo, liquid cargo, or mixed bulk and dry cargo, the package including the machinery section 14, and superstructure 24 can be installed upon the hull 11 to provide the proper trim function. The package arrangement, including the "pods," has the further advantage of enabling a degree of standardization to be provided in ship construction since a package of a given design may be used with a variety of hull types.

The machinery section 14 contains an appropriate prime mover, such as a gas turbine engine 51, which may include an air compressor 52 to operate auxiliary equipment. A turbine output shaft 53 drives electric generators 54 and 55, the current from which is carried to the propulsion units 15a and 15b by feeder cables after passage through a power control unit 56.

Auxiliary machinery associated with ship propulsion and control (as distinguished from cargo handling) such as pumps, standby power supplies, etc., may also be installed in the machinery section 14. With this arrangement, the spaces and platforms within the hull are essentially entirely free of propulsion machinery and propulsion auxiliaries. The only such equipment passing through or located within the hull and its platforms is that of feeder cables to the propulsion units 15a and 15b. Of course the hull does contain the steering engine and related equipment associated with ship control. Fuel for the gas turbine engine 51 is stored in tanks 33 and 34 adjacent the machinery section 14 so that fuel piping runs from these tanks to this engine are quite short. The superstructure section 24 contains a plurality of decks 24a, 24b, 24c, etc., upon which are located staterooms and the operations rooms and compartments used for navigation and control of the vessel.

The propulsion unit 15b, taken as exemplary, includes a housing 57 in which are mounted one or more propulsion motors 19 connected by a drive shaft 58 to a reduction gear 59. Co-axial propeller shafts 60 extend from the reduction gear 59 through a shaft bearing to the two

co-axially mounted propellers 17 and 18. Electrical power from the prime mover unit is delivered to the motors by means of feeder cables 20. Where the propulsion motor or motors can operate at propeller shaft speed, the reduction gear 59 may be eliminated and direct drive employed. With the package or unit arrangement, the propulsion unit 15b is secured to the stern surface 21 of the hull 11, and may be replaced by another unit without immobilizing the vessel for an extended time. Each propulsion unit may be streamlined by providing it with a substantially circular or elliptical cross section and with fairings between the major body portion of the housing 57 and surface 21 in order to permit the proper flow of water to the propellers, and thus gain a propulsive efficiency equal to or greater than that of conventional ships. With the propulsion units 15a and 15b outside the hull 11, it is clear that additional space in the interior of the hull is available for cargo stowage.

Referring next to FIGS. 4, 5, and 6, a tanker 110 constructed according to the present invention has a hull 111 having a main or freeboard deck 112, and on which there is mounted a midships or forward superstructure section 124 and an aft superstructure section including a machinery section 114. Within the midships superstructure section on a tank deck there are structural fuel oil tanks 133a through 133f (port) and 134a through 134f (starboard). Within the aft superstructure section there are structural fresh water tanks 125a, 125b, and 125c. These tanks may be appropriately divided individually into port and starboard tank portions. Otherwise tanker 110 is similar in all essential respects to tanker 10 shown in FIGS. 1, 2, and 3 so far as having incorporated within its design the various features and advantages particularly characteristic of and deriving from the present invention.

The advantages deriving from the present invention are demonstrated further by way of certain particular comparisons given in Table III. The first data column of this table sets forth a number of parametric values and specific measurements for standard tanker "F" of Table II, this tanker having a total deadweight carrying capacity of 66,532 tons. The second data column sets forth the corresponding parametric values and specific measurements for a tanker designed according to this invention to have the same total deadweight of 66,532 tons as the standard ship taken as a reference, with a hull that is shorter by about twelve percent (LBP reduced from 770 ft.-10 in. to 675 ft.-0 in.). In the case of the inventive tanker, of course, essentially none of the propulsion machinery is located within the structural hull.

Table III

	Ship	Standard Tanker (Ship F, Table II)	Inventive Tanker, Comparable Dwt.
55			
LBP (ft.-in.)	770-10	675-0	
B, molded (ft.-in.)	104-0	121-0	
D, molded (ft.-in.)	60-0	55-0	
H, molded (ft.-in.) ¹	44-7	44-4	
G ₁	0.806	2.825	
L _{OT} (ft.-in.)	492-0	505-0	
Cargo Cubic (cu. ft.)	2,631,500	2,631,500	
B/H	2.33	3.00	
L/D	12.85	12.27	
LCT/LBP	0.638	0.750	
Net Steel (tons)	12,896	8,950	
Light Ship (tons)	16,146	12,600	
Cargo Oil (tons)	62,174	62,174	
Dwt., total (tons)	66,532	66,532	
Δ, total (tons)	82,678	78,532	
Dwt./Δ	0.805	0.845	
Net Steel/Cargo	0.207	0.144	

¹ Summer freeboard.² Calculated using LBP as length dimension.

Considering particularly the last three rows of data, it will be seen first of all that the inventive or prototype tanker has a total displacement which is about five percent less than that of the standard ship (Δ reduced from 82,678 tons to 78,532 tons). This reduction in displace-

ment is due to a reduction in light ship weight, predominantly in steel weight (net steel weight reduced from 12,896 tons to 8,950 tons), since total deadweight has been held constant. There has been about a five percent increase and hence improvement in the ratio of total deadweight to total displacement calculated on the basis of the original value of this ratio. (D_{wt}/Δ increased from 0.805 to 0.845). Furthermore, there has been about a thirty percent decrease and hence improvement in the ratio of net steel weight to cargo oil weight (Net Steel/Cargo decreased from 0.207 to 0.144). With respect to the selected standard ship of Table III, therefore, the inventive or prototype ship is indeed a ship of reduced structural weight for given cargo weight carrying capacity, just according to the title of this invention. Conversely, with respect to standard tankers of approximately equivalent length and steel hull weight such as hulls "C" and "D" of Reference B, the inventive or prototype ship has a startling superiority in cargo carrying ability.

Protection by Letters Patent of the present invention in all its aspects as the same are set forth in the appended claims is sought to the broadest extent that the prior art allows.

What is claimed is:

1. A self-propelled ocean-going surface cargo ship having a ratio of total deadweight to total displacement of at least 0.80:1 and comprising a hull which is characterized by (1) a ratio of length between perpendicularly to molded depth not greater than 13.30:1 and (2) a ratio of molded beam to molded draft at summer freeboard not less than 2.80:1, essentially all of the propulsion machinery of said ship being located outside of said hull and including a prime mover unit which is substantially fixedly attached to said hull and derives buoyant support therefrom.

2. A self-propelled ocean-going surface cargo ship according to claim 1 which has a ratio of net steel weight to full load cargo weight not greater than 0.190:1.

3. A self-propelled ocean-going surface cargo ship according to claim 1 which has a ratio of net steel weight to full load cargo weight in the range from 0.140:1 to 0.180:1.

4. A self-propelled ocean-going surface cargo ship having a ratio of total deadweight to total displacement of at least 0.80:1 and comprising a hull which is characterized by (1) a ratio of length between perpendicularly to molded depth not greater than 13.30:1, (2) a ratio of molded beam to molded draft at summer freeboard not less than 2.80:1, and (3) a block coefficient not less than 0.80, essentially all of the propulsion machinery of said ship being located outside of said hull and including a prime mover unit which is substantially fixedly attached to said hull and derives buoyant support therefrom.

5. A self-propelled ocean-going surface cargo ship according to claim 4 having a ratio of total deadweight to total displacement in the range from 0.81:1 to 0.86:1.

6. A self-propelled ocean-going surface cargo ship according to claim 4 in which the hull is characterized by a ratio of length between perpendicularly to molded depth in the range from 11.50:1 to 13.00:1.

7. A self-propelled ocean-going surface cargo ship according to claim 4 in which the hull is characterized by a ratio of molded beam to molded draft at summer freeboard in the range from 2.90:1 to 3.10:1.

8. A self-propelled ocean-going surface cargo ship according to claim 4 in which the hull is characterized by a block coefficient in the range from 0.81 to 0.85.

9. A self-propelled ocean-going surface tank ship for the carriage of liquid cargoes, said ship having a ratio of total deadweight to total displacement of at least 0.80:1 and comprising a hull which is characterized by a ratio of length of below-deck cargo tank space to length between perpendicularly not less than 0.70:1, and essentially all of the propulsion machinery of said ship being located outside of said hull and including a prime mover

unit which is substantially fixedly attached to said hull and derives buoyant support therefrom.

10. A self-propelled ocean-going surface tank ship for the carriage of liquid cargoes according to claim 9 in which the hull is characterized by a ratio of length of below-deck cargo tank space to length between perpendicularly in the range from 0.70:1 to 0.82:1.

11. A self-propelled ocean-going surface tank ship for the carriage of liquid cargoes, said ship having a ratio of net steel weight to full load cargo weight not greater than 0.190:1 and comprising a hull which is characterized by a ratio of length of below-deck cargo tank space to length between perpendicularly not less than 0.70:1, and essentially all of the propulsion machinery of said ship being located outside of said hull and including a prime mover unit which is substantially fixedly attached to said hull and derives buoyant support therefrom.

12. A self-propelled ocean-going surface tank ship for the carriage of liquid cargoes according to claim 11 in which the hull is characterized by a ratio of length of below-deck cargo tank space to length between perpendicularly in the range from 0.70:1 to 0.82:1.

13. A self-propelled ocean-going surface cargo ship having a ratio of total deadweight to total displacement of at least 0.80:1 and comprising (1) a hull having a freeboard deck and characterized by (i) a ratio of length between perpendicularly to molded depth not greater than 13.30:1, (ii) a ratio of molded beam to molded draft at summer freeboard not less than 2.80:1, and a block coefficient not less than 0.80; (2) a prime mover unit positioned at a level at least as high as that of the freeboard deck, said prime mover unit having means for providing a source of energy to propel the ship, and (3) at least one propulsion unit located below the water line at the stern of the ship and secured to the exterior surface of said hull, said propulsion unit comprising (i) a propulsion motor adapted to be energized by said energy providing means and (ii) propulsion means actuated by said propulsion motor for propelling the ship.

14. A self-propelled ocean-going surface cargo ship according to claim 13 further comprising structural fuel oil tanks for said prime mover located at a level at least as high as that of the freeboard deck.

15. A self-propelled ocean-going surface cargo ship according to claim 13 further comprising structural fresh water tanks located at a level at least as high as that of the freeboard deck.

16. A self-propelled ocean-going surface cargo ship having a ratio of total deadweight to total displacement of at least 0.80:1 and comprising (1) a hull having a freeboard deck and a scow-type stern, (2) a prime mover unit positioned at a level at least as high as that of the freeboard deck, said prime mover unit having means for providing a source of energy to propel the ship, and (3) at least one propulsion unit located below the water line at the stern of the ship and secured to the exterior surface of said hull, said propulsion unit comprising (i) a propulsion motor adapted to be energized by said energy providing means, (ii) at least one pair of co-axially mounted propellers, and (iii) means for transmitting power from said propulsion motor to said propellers.

17. A self-propelled ocean-going surface cargo ship having a ratio of total deadweight to total displacement of at least 0.80:1 and comprising (1) a hull having a freeboard deck and a scow-type stern and characterized by (i) a ratio of length between perpendicularly to molded depth not greater than 13.30:1, (ii) a ratio of molded beam to molded draft at summer freeboard not less than 2.80:1, and (iii) a block coefficient not less than 0.80; (2) a prime mover unit positioned at a level at least as high as that of the freeboard deck, said prime mover unit having means for providing a source of energy to propel the ship, and (3) at least one propulsion unit located below the water line at the stern of the ship and secured to the exterior surface of said hull, said propulsion unit comprising (i)

a housing, (ii) a propulsion motor within said housing adapted to be energized by said energy providing means, (iii) at least one pair of coaxially-mounted contra-rotating propellers exterior to said housing and oriented to provide thrust along the longitudinal axis of said ship, and (iv) means for transmitting power from said propulsion motor to said contra-rotating propellers.

18. A self-propelled ocean-going surface cargo ship having a ratio of total deadweight to total displacement of at least 0.80:1 and comprising (1) a hull having a freeboard deck and characterized by (i) a ratio of length between perpendiculars to molded depth not greater than 13.30:1, (ii) a ratio of molded beam to molded draft at summer freeboard not less than 2.80:1, and (iii) a block coefficient not less than 0.80; (2) a prime mover unit positioned at a level at least as high as that of the freeboard deck near the stern of the ship, said prime mover unit having means for providing a source of energy to propel the ship, and (3) at least one propulsion unit located below the water line at the stern of the ship and secured to the exterior surface of said hull not lower than a horizontal plane passing through the keel thereof, said propulsion unit comprising (i) a housing, (ii) a propulsion motor within said housing adapted to be energized by said energy providing means, (iii) at least one pair of co-rotating propellers oriented to provide thrust along the longitudinal axis of the ship, and (iv) means for transmitting power from said propulsion motor to said co-rotating propellers.

19. A self-propelled ocean-going surface cargo ship having a ratio of total deadweight to total displacement of at least 0.80:1 and comprising (1) a hull having a freeboard deck and characterized by a ratio of length between perpendiculars to molded depth not greater than 13.30:1, (ii) a ratio of molded beam to molded draft at summer freeboard not less than 2.80:1, and (iii) a block coefficient not less than 0.80; (2) a pair of bulkheads within said hull extending longitudinally for substantially the full length of the hull and vertically for substantially the full depth of the hull, said bulkheads being fairly closely spaced and defining an open space between them, (3) a plurality of tank spaces defined outboard of said bulkheads between these bulkheads and the hull, these tank spaces being adapted to receive liquid cargo, (4) a prime mover unit positioned at a level at least as high as that of the freeboard deck, said prime mover unit having means for providing a source of energy to propel the ship, (5) at least one propulsion unit located below the water line at the stern of ship and secured to the exterior surface of said hull, said propulsion unit being adapted to be energized by said energy providing means, and (6) means for transmitting power from said prime mover unit to said propulsion unit.

20. A self-propelled ocean-going surface tank ship for the carriage of liquid cargoes, said ship comprising (1) a hull having a freeboard deck and characterized by a ratio of length of below-deck cargo tank space to length between perpendiculars not less than 0.70:1, (2) a prime mover unit positioned at a level at least as high as that of the freeboard deck, said prime mover unit having means for providing a source of energy to propel the ship, and (3) at least one propulsion unit located below the water line at the stern of the ship and secured to the exterior surface of said hull, said propulsion unit comprising (i) a propulsion motor adapted to be energized by said energy providing means and (ii) propulsion means actuated by said propulsion motor for propelling said ship.

21. A self-propelled ocean-going surface tank ship for the carriage of liquid cargoes, said ship comprising (1) a hull having a freeboard deck, (2) a pair of bulkheads within said hull extending longitudinally for substantially the full length of the hull and vertically for substantially the full depth of the hull, said bulkheads being substantially equally and oppositely offset from a vertical longi-

tudinal centerline plane through said hull, and defining an open space between them having a width of not more than about ten percent of the beam of the ship at its midship section, (3) a plurality of tank spaces defined outboard of said bulkheads between these bulkheads and the hull, these tank spaces being adapted to receive liquid cargo and the ratio of the length of the hull through which said tank spaces extend to the length between perpendiculars thereof being not less than 0.70:1, (4) a prime mover unit positioned at a level at least as high as that of the freeboard deck, said prime mover unit having means for providing a source of energy to propel the ship, (5) at least one propulsion unit located below the water line at the stern of the ship and secured to the exterior surface of said hull, said propulsion unit comprising (i) a propulsion motor adapted to be energized by said energy providing means and (ii) propulsion means actuated by said propulsion motor for propelling said ship, and (6) means extending through the space between said bulkheads for transmitting power from said prime mover unit to said propulsion unit.

22. A self-propelled surface cargo ship of reduced structural weight for given cargo weight carrying capacity, said ship comprising (1) a hull having a freeboard deck, (2) at least one pair of bulkheads within said hull extending longitudinally for substantially the entire length of the hull and vertically for substantially the entire depth of the hull, said bulkheads being fairly closely spaced in respect of the overall beam of the hull and defining an open space between them and cargo spaces on both sides of the pair of them, (3) a prime mover unit positioned at a level at least as high as that of the freeboard deck, said prime mover unit having means for providing a source of energy to propel the ship, (4) at least one propulsion unit extending from the exterior of said hull below the water line but not lower than the keel line thereof, said propulsion unit comprising (i) at least one propulsion motor adapted to be energized by said energy providing means and (ii) propulsion means actuated by said propulsion motor for propelling the ship, and (5) power transmitting means extending from said energy providing means to said propulsion unit.

23. A self-propelled surface cargo ship of reduced structural weight for given cargo weight carrying capacity, said ship comprising (1) a hull having a freeboard deck, (2) a pair of bulkheads within said hull extending longitudinally for substantially the entire length of the hull and vertically for substantially the entire depth of the hull, said bulkheads being fairly closely spaced in respect of the overall beam of the hull on either side of a vertical longitudinal centerline plane through the hull and defining an open space between them, (3) a plurality of bulkheads extending transversely within said hull and defining a plurality of longitudinally arrayed cargo spaces outboard of the longitudinally extending bulkheads between these bulkheads and the hull, these cargo spaces being adapted to receive liquid bulk cargo and in the aggregate on either side of said pair of bulkheads occupying the considerably greater part of the length of the hull as well as individually extending substantially the full depth thereof, (4) a prime mover unit positioned at a level at least as high as that of the freeboard deck, said prime mover unit having means for providing a source of energy to propel the ship, (5) at least one propulsion unit extending from the exterior of said hull below the water line but not lower than the keel line thereof, said propulsion unit comprising (i) at least one propulsion motor adapted to be energized by said energy providing means and (ii) propulsion means actuated by said propulsion motor for propelling the ship, and (6) power transmitting means extending from said energy providing means to said propulsion unit.

24. A self-propelled surface cargo ship of reduced structural weight for given cargo weight carrying capacity, said ship comprising (1) a hull having (i) a free-

board deck and (ii) a stern portion of substantially rectangular vertical cross section at its forward end and having a substantially flat bottom surface extending rearwardly in an upwardly inclined direction from the lower edge of said forward end and further having substantially vertical and rearwardly converging side surfaces, (2) a prime mover unit positioned at a level at least as high as that of said freeboard deck, said prime mover unit having means for providing a source of energy to propel the ship, (3) at least one propulsion unit extending rearwardly from the upwardly inclined bottom surface of the stern portion of said hull below the water line but not lower than the keel line thereof, said propulsion unit comprising (i) at least one propulsion motor adapted to be energized

5

by said energy providing means and (ii) propulsion means actuated by said propulsion motor for propelling the ship, and (4) power transmitting means extending from said energy providing means to said propulsion unit.
